(57) **CLAIM**

The ornamental design for a trailer trash trashcan, as shown and described.

DESCRIPTION

FIG. 1 is an upper front left oblique view of the trailer trash trashcan showing our new design;

FIG. 2 is the left side elevation view of the trashcan, thereof;

FIG. 3 is the right side elevation view of the trashcan, thereof;

FIG. 4 is the top view of the trashcan, thereof;

FIG. 5 is the bottom view of the trashcan, thereof;

FIG. 6 is an isometric view of the bottom of the trashcan

thereof;

FIG. 7 is the front elevation view of the trashcan, thereof;

FIG. 8 is the rear elevation view of the trashcan, thereof;

FIG. 9 is the rear elevation view of the trashcan, showing the vertical cross-section demarcation line for the longitudinal

cross-sectional view seen in FIG. 10, thereof;

FIG. 10 is a cross-sectional longitudinal view of the trashcan,

showing the interior detail thereof; and,

FIG. 11 is an upper rearward left oblique view of the trashcan

showing the interior detail thereof.
